United States Patent Office

Des. 188,535
Patented Aug. 9, 1960

188,535

VEHICLE MIRROR

Roger H. David, Sr., 818 Chippewa, St. Paul, Minn.

Filed June 8, 1959, Ser. No. 56,244

Term of patent 7 years

(Cl. D14—6)

Figure 1 is a front elevational view of a vehicle mirror showing my new design.

Figure 2 is a rear elevational view thereof.

Figure 3 is a top plan view.

Figure 4 is an end view.

Figure 5 is an end view opposite to that shown in Figure 4.

The essential features of my design reside in the portions shown in full lines.

I claim:

The ornamental design for a vehicle mirror, as shown and described.
